UNITED STATES PATENT OFFICE.

ALFRED H. RUSH, OF PHOENIXVILLE, PENNSYLVANIA.

TITLE-MAKING MACHINE.

Application filed April 12, 1922. Serial No. 551,909.

To all whom it may concern:

Be it known that I, ALFRED H. RUSH, a citizen of the United States, residing at Phoenixville, in the county of Chester and State of Pennsylvania, have invented certain new and useful Improvements in Tile-Making Machines, of which the following is a specification.

This invention relates to tile making machines, and it comprises means for forming the body of the tile, means for applying coloring matter to the surface of the tile, means for smoothing the surface of the tile, and means for ejecting the tile from the machine.

An object of the invention is the provision of a machine having a former consisting of side and end walls adapted to receive a platen to form the lower face of the tile, and a reciprocating member adapted to pass over the former to cut the upper surface of the tile.

A further object of the invention is the provision of a pivoted locking member adapted to engage one end of the tile to hold it in position, and combined means for releasing said member and raising the tile from the machine.

A further object of the invention is the provision of means for applying coloring matter to the surface of the tile and smoothing the surface after the coloring matter has been applied.

The coloring matter is arranged in powdered form in a receptacle having a perforated bottom which is mounted to swing over the tile in the former, and is loosely supported to permit vibration to sift the coloring matter on to the surface of the tile.

In the accompanying drawings, I have shown one embodiment of the invention. In this showing:

Figure 1 is a plan view;

Figure 2 is a side elevation;

Figure 3 is an end elevation;

Figure 4 is a longitudinal vertical sectional view on line 4-4 of Figure 1;

Figure 5 is a perspective view of the platen adapted to be arranged within the former;

Figure 6 is a view similar to Figure 4, showing the mechanism released;

Figure 7 is a detail view of the color applying apparatus, 55

Figure 8 is a vertical transverse sectional view on line 8-8 of Figure 2,

Figure 9 is a detail view of the locking and releasing mechanism,

Figure 10 is a transverse sectional view 60 on line 10-10 of Figure 2, and,

Figure 11 is a detail view of the pivoted locking member.

Referring to the drawings, the reference numeral 1 designates the legs of the machine which are adapted to receive and support a pair of longitudinal side bars 2. A substantially rectangular supporting frame is formed of substantially L-shaped beams 3, the ends of which are secured to the legs 70 and side bars in any suitable manner. This supporting frame is adapted to receive and support a former which consists of vertical walls 4, and a platen 5 adapted to be received within the vertical walls. Referring to Figure 5 of the drawings, 75

the platen consists of a substantially flat plate having offset end portions 6, and provided with suitable ribs 7 to produce a tile of a desired design. A reciprocating member 8 is mounted on the side bars and is adapted to move over a body of cement arranged in the former to produce an upper surface conforming to the surface produced by the platen 5. The member 8 is provided with suitable grooves and is adapted to slide upon the side bars. The rearward movement of this member is limited by a stop 9, arranged adjacent the rear end of one of the side bars. Suitable 80

brackets 10 are arranged adjacent the rear end of the member 8, adapted to receive and support a shaft 11. A supporting frame 12 is pivotally mounted on this shaft. As shown, the frame is provided with a pair 85

of arms 13 and a bushing 14 arranged at the ends of the arms and adapted to surround the shaft. A latch 15 is pivotally mounted on the pin 16, carried by one of the arms 13, and this latch is adapted to engage a notch 17, in one of the side bars 90

of the frame 8 to retain the supporting frame in raised position. The supporting frame is provided with a pair of depending bearing arms 18 arranged adjacent each side and these are adapted to receive stub 100

shafts 19 pivotally supporting a cutter block 20. The cutter block is provided with a lower face 21 of a design similar to the design of the platen 5, to produce the desired configuration on the upper face of the tile. As stated, the cutter block is pivotally supported in the supporting frame 12, but means are provided whereby the cutter block may be locked to the supporting frame 10 to prevent independent movement. As shown (see Figure 4), the forward end of the cutter block is provided with a shoulder 21' and a bar 22 is received in this shoulder and projects upwardly therefrom. 15 This bar carries an operating handle 23'. The supporting frame is provided with a projecting tooth 23 adapted to engage notches 24 or 25, carried by a latch 26. As shown, this latch is pivoted on the handle 20 by means of a pin 27 and is normally forced toward the supporting frame by a spring 28. An operating member 29 is also pivoted on the handle 23' by means of a pin 30 and this member is provided with a projection 31, engaging one end 32 of the latch. The operating member 29 is provided with a finger grip 33, to permit operation of the latch. The cutter bar may be vertically adjusted by means of an adjusting screw 34 25 carried by the supporting frame provided with a lock nut 35 and may be angularly adjusted by means of an adjusting screw 36 carried by the supporting frame and having a lock nut 37. The forward end of the cutting bar is provided with a cutting edge 38. As stated, the platen is mounted within the frame 4 and is adapted to rest upon the L-shaped bars 3. Means are provided for locking the platen in position for releasing 40 and ejecting it when desired. A shaft 39 is mounted in suitable bearings arranged on the front legs of the machine, and this shaft is adapted to support a locking member 40. The locking member extends to the top of the machine and is provided with a pair of legs 41 having suitable bushings 42 on their lower ends adapted to receive the shaft. A substantially L-shaped plate 43 is carried on the upper end of the locking member and 45 the horizontal portion of this plate is provided with an edge 44 adapted to project beyond the adjacent edge of the frame. When a tile 45 is arranged in the former and the reciprocating member 8 is moved 50 forwardly, it engages the outer edge 46 of the L-shaped plate forming a shoulder 47 of cement beneath it to lock the tile in the former. The L-shaped plate is provided with a pin 48, which is adapted to project through an opening in the plate 4 to form a nail receiving opening in the tile. The locking member is forced to the unlocked position shown in Figure 6 of the drawings by means of a spring 49, one end of which 55 is received by a stud 50, carried by the

locking member and the other end received by a stud 51, carried by the frame of the former. The locking member is provided with a latch 52 pivotally mounted on a pin 53, carried by the arms 41, and the inner end of this latch passes through an opening in a sleeve 54, carried by the frame of the former. As shown, the latch is provided with a latch tooth 55, which is adapted to engage the inner edge of the sleeve 54 75 when in locked position (see Figure 4). The locking member is provided with an operating member 56, which is loosely mounted on a bolt 57 to permit slight relative movement of the locking member and the member 56. The member 56 passes through the guide 57 and is provided with a cut-out portion 58. As shown, one end of the cut-out portion is provided with an inclined wall 59. 80 85

A pair of shafts 60 are mounted in suitable bearings beneath the former and these shafts are provided with crank arms 61, connected by a link 62. One of the shafts is provided with a crank 63, whereby operation of the cranks will oscillate the two shafts in unison. 90

The shafts are provided with combined latch releasing and lifting members 64, which are secured to the shafts to revolve therewith. Each of these members consists of an arm 65 which is adapted to be received in the recess 58. When the shafts are revolved in a counter-clockwise direction in Figure 4 of the drawings, the faces of these arms engage the ends of the recesses to move the members 64 to the right and draw the locking member to operating position. When moving in the reverse direction, the arms travel over the inclined faces 59 and have no effect on the operation of the machine. The members 64 are further provided with a radially extending portion 66 having a pair of projections 67 and 68. The projection 67 is adapted to engage the end of latch 52 and raise it so that the bottom of the tooth 55 will clear the opening in the sleeve 54, and permit the spring 49 to move the locking member outwardly. Further revolution of the shafts in a clockwise direction causes the projection 68 to engage the bottom of the platen, as shown in Figure 6 of the drawings and raise it to permit removal of the tile. 100 105 110 115 120

One of the legs of the machine is provided with a bracket 68'. This bracket is adapted to receive a plate 69, having a bearing 70 formed thereon. A second bearing 71 is arranged in alignment therewith. The apparatus for holding the coloring matter is mounted on this shaft and is adapted to be swung from the position shown in Figure 1 of the drawings to the position above the former, shown in Figure 3 of the drawings. As shown, this member comprises a frame 72 125 130

having an arm 73 projecting therefrom. This arm is provided with a bushing 74 adapted to receive a shaft 75, mounted in the bearings 70 and 71. The frame is also 5 provided with a depending arm 76, having a bushing 77 through which the shaft 75 passes. The arm 76 is provided with a notch 78 which is adapted to receive the adjacent bar 2 of the machine when the 10 device is in operative position (see Figure 3). The bars 2 are provided with adjusting screws 79 which are suitably supported in the legs of the machine and are provided with lock nuts 80.

15 The apparatus for holding the coloring matter consists of a box 81 provided with a perforated bottom 82. This box is adapted to be arranged over the frame 72 and is provided with guide members 83 arranged 20 on opposite sides and adapted to retain the box against transverse movement with respect to the frame. As shown, one of these members is provided with a notched end 84, adapted to be received in an elongated slot 25 85 of the arm 73. Runners 86 are arranged on the under side of the box and extend longitudinally thereof. These runners are provided with offset ends 87. The distance between the ends of the runners is greater than 30 the length of the frame which permits the box to be moved longitudinally of the frame to sift coloring matter through the perforated bottom 82. A chute 88 is arranged beneath the former, adapted to receive excess 35 material removed from the face of the tile by the cutter block. The material is conveyed to a suitable point and reused if desired.

In operation, a platen 5 is first placed in 40 the former 4 and a quantity of cement or other material from which the tile is to be formed is arranged thereon. The locking member and lifting devices are arranged in the position shown in Figure 4 of the drawings. If the parts are in the position shown 45 in Figure 6 of the drawings, the shafts 60 are revolved in a counter-clockwise direction and the arm 65 engages the end of the recess 58, moving the plate 56 to the left and drawing the locking member inwardly 50 against the tension of the spring 49. As the locking member moves inwardly, the tooth 55 of latch 52 drops into locked position by gravity. At the same time, the arms 67 and 68 are lowered and the platen assumes 55 a normal position when placed in the former. The reciprocating member 8 is first arranged with the tooth 23 in the notch 24. This position 60 the lower face 21 of the cutter block 20 in a plane substantially parallel to the platen. The reciprocating member is moved forwardly in a raised position by holding the handle 23' up and is lowered when it reaches the point where the face 46 of the 65 locking member prevents further forward

movement. The reciprocating member is then moved rearwardly over the cement and the cutting edge 38 of the cutter block removes excess material which falls into the chute 88. With the reciprocating member 70 at the rear of the machine, the coloring apparatus is swung to the position shown in Figure 8 of the drawings and the box vibrated by hand to sift the desired amount of coloring matter on the surface of the tile. 75 The finger piece 33 of the latch operating member 29 is then depressed to release the tooth 23. By swinging the handle 23' with the latch released, the tooth 23 is caused to enter the notch 25 which arranges the 80 cutter bar at a slight angle as shown in Figure 4 of the drawings, and leaves the cutting edge 38 above the surface of the tile. The reciprocating member is then passed over the surface of the tile with the 85 face 21 engaging the surface of the tile to force the coloring material into the surface of the tile and produce a smooth, polished surface.

By revolving the shafts 60 in a clockwise 90 direction, the arm 65 is first withdrawn from the recess 58 and the projection 67 then lifts the latch to release it. The locking member then moves to the position shown in Figure 6 95 of the drawings actuated by spring 49, releasing the shoulder 47 of the tile and the tile is then lifted by engagement of the projections 68 and the under surface of the platen. The tile is then removed and the 100 operation repeated.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I 110 claim:

1. A tile making machine comprising a former having an open top, said former being adapted to receive material to form said tile, a cutter bar adapted to be reciprocated over said former to remove excess material therefrom, and means for locking said former during the formation of said tile.

2. A tile making machine comprising a former having an open top, said former being adapted to receive material to form said tile, a cutter bar adapted to be reciprocated over said former to remove excess material therefrom, means for locking said former during the formation of said tile, and means for raising said tile to release it from said former.

3. A tile making machine comprising a former having an open top, said former being adapted to receive material from which a tile is to be formed, means for removing 130

- excess material from the top of said former, and means for applying coloring matter thereto, said excess removing means being adapted to smooth the surface of the tile 5 after the application of the coloring matter.
4. A tile making machine comprising a former having an open top, said former being adapted to receive material from which a tile is to be formed, and common means for 10 removing excess material from the top of said former and smoothing the surface of the tile.
5. A tile making machine comprising a former having an open top, said former being adapted to receive material from which a tile is to be formed, means for removing 15 excess material from the top of said former, means for applying coloring matter to the surface of the tile, and means for adapting 20 said excess removing means for smoothing the surface of the tile.
6. In a tile making machine, a former having an open top, a reciprocating member arranged above said former, a pivoted cutter 25 bar carried by said reciprocating member, and means for supporting said cutter bar in either of two positions.
7. A tile making machine comprising a former having an open top, a cutter bar 30 adapted to be reciprocated over said former, and a pivoted locking member having a portion extending over said former to retain said former during the formation of said tile.
8. A tile making machine comprising a former having an open top, a cutter bar 35 adapted to be reciprocated over said former, a pivoted locking member having a portion extending over said former to retain said former during the formation of said tile, and means for raising said tile in said former to permit its removal therefrom.
9. A tile making machine comprising a former having an open top, a cutter bar 40 adapted to be reciprocated over said former, a pivoted locking member having a portion extending over said former to retain said former during the formation of said tile, means for locking said member in operative 45 position, and means for raising said tile in said former to permit its removal therefrom, said means being adapted to release said pivoted locking member.
10. A tile making machine comprising a former having an open top, a swinging frame mounted over said former, and a receptacle carried by said frame, said receptacle being provided with a perforated bottom and being further provided with 50 depending guides on its sides and ends adapted to engage said frame, the end guides being spaced from each other a greater distance than the length of the frame to permit vibration of said receptacle.
11. In a tile making machine, a former 55 having an open top, a member adapted to reciprocate over said former, a pivoted cutter bar carried by said member, said member being provided with a tooth, and said cutter bar being provided with a plurality of 60 notches to receive said tooth to permit adjustment of the angle of said cutter bar.
12. In a tile making machine, a former having an open top, a member adapted to reciprocate over said former, a pivoted cutter bar carried by said member, said member being provided with a tooth, and said cutter bar being provided with a plurality 65 of notches to receive said tooth to permit adjustment of the angle of said cutter bar, and a latch to retain said tooth in engagement with one of said notches.
13. A tile making machine comprising a former having an open top, a cutter bar adapted to be reciprocated over said former, a pivoted locking member having a portion 70 extending over said former, means carried by said locking member for forming an opening in the tile being formed, and common means for releasing said locking member and raising the tile in said former to permit its removal therefrom.
14. A tile forming machine comprising a former having an open top, a platen arranged in said former, a reciprocating cutter bar mounted upon said former, means for raising said platen, a pivoted member having a portion extending over said former when said platen is in normal position, means for locking said pivoted member in normal position, and means carried by said first named means for unlocking said pivoted member when said platen is raised.
15. A tile forming machine comprising a former having an open top, a platen arranged in said former, a reciprocating cutter bar mounted above said former, means for raising and lowering said platen, a pivoted member having a portion extending over said former when said platen is in normal position, means for locking said pivoted member in normal position, and common means carried by said first named means for unlocking said pivoted member when said platen is raised and locking it when said platen is lowered.
16. A tile forming machine comprising a former having an open top, a platen arranged in said former, a cutter bar adapted to be reciprocated over said former, a pair of rock-shafts below said platen, means carried by said shafts for raising said platen, a pivoted member having a portion extending over said former when said platen is in normal position, means for locking said pivoted member in normal position, and means carried by one of said rock-shafts for unlocking said pivoted member.
17. A tile forming machine comprising a former having an open top, a platen ar-

ranged in said former, a cutter bar adapted to be reciprocated over said former, a pair of rock-shafts mounted below said platen, means carried by said shafts for raising and 5 lowering said platen, a pivoted member having a portion extending over said former when said platen is in normal position, means for locking said pivoted member in normal position, and means carried by one 10 of said rock-shafts for unlocking said pivoted member when said platen is raised and locking it when said platen is lowered.

18. A tile forming machine comprising a former having an open top, a member 15 mounted to reciprocate above said former,

a pivoted frame carried by said reciprocating member and adapted to be moved to operative and inoperative positions, a cutter block carried by said pivoted frame and normally arranged with its lower face parallel to the surface of the tile being formed, and means for tilting said block independently of said pivoted frame. 20

In testimony whereof I affix my signature in presence of two witnesses.
